GASOLINE NOZZLE

Valentine Fina and William F. Hoelzer, Milwaukee, Wis., assignors to Milwaukee Valve Company, Milwaukee, Wis., a corporation of Wisconsin

Application April 18, 1940, Serial No. 330,256

6 Claims. (Cl. 251—134)

Our invention pertains to valved dispensing nozzles.

The primary object of the invention is to provide an improved valved nozzle in which a novel and improved valve operating mechanism is effectively sealed against leakage and yet is easily and smoothly operable, economically manufactured and easily assembled and repaired.

Valve mechanisms for manually controlling deliveries of gasoline and similar fluids of high penetrating and volatile characteristics present problems not encountered in the use of valved nozzles for similarly controlling water deliveries. Gasoline is relatively expensive, and leakage also involves fire hazards, to say nothing of atmospheric pollution by the fumes. We find that while manually operable valves for regulating delivery of gasoline through outlet ducts or nozzles should be of that type in which the valves close with the pressure of the fluid, aided by spring pressure to ensure positive and uniform seating, yet these valves should not be allowed to snap shut but should be opened and closed in a graduated movement, whereby the durability and effectiveness of the valve cannot be impaired by careless operation.

We find that the problem of providing a suitable manually controlled gasoline valve is peculiar to the gasoline and allied industries, and our object is to effectively solve that problem.

A further object is to provide an organization of lever, pivot and sealing members whereby upon removal of the sealing member the pivot and lever members are exposed for disassembly and assembly.

Another object is to provide an improved lever system for manual operation.

Other objects and advantages of the invention will become apparent during description of the art and following an examination of the following specification, drawing, and claims attached thereto.

In the drawing.

Fig. 1 is a figure of elevation of a hose nozzle and control mechanism having my invention incorporated therein.

Fig. 2 is a sectional view of elevation of the nozzle disclosed in Fig. 1.

Fig. 3 is a fragmentary section view of an alternate embodiment valve actuating mechanism.

Like parts are identified by the same reference characters throughout the several views.

The invention is particularly adapted for incorporation in the type of hose nozzle used in

dispensing gasoline. This type of nozzle as shown in Fig. 1 includes generally a hollow casing 10 which may have an end portion 11 arcuately curved. Casing 10 is provided with threaded end portions to receive respectively a special hose coupling 12 and outlet conduit 13. A bracket or guard 14 is carried by the casing to provide support and protection for a handle 15 which has one end portion fulcrumed thereto. 5

10 A relatively short lever 16 also has an end portion fulcrumed to the bracket in a position whereby a roller 17 carried by handle 15 follows a curved cam portion of lever 16 to provide compound lever movement whereby lever 16 is 15 fulcrumed through an arc offset about 90° from the arc through which handle 15 moves in the course of its pivotal movement.

10 The valve control mechanism includes lever 21 which is pivoted to the valve casing 10 for transmission of motion from lever 16 to a valve which is hereinafter described.

20 Casing 10 is divided interiorly by a valve seat partition 22 into an inlet chamber 23 and an outlet chamber 24. A plug valve 26 is disposed 25 within chamber 23 for normal seating engagement with seat 22. Valve 26 is biased toward seat 22 by compression spring 27 which has one end encircling gasket retaining nut on valve 26 and the opposite end encircling a boss of spider 30 25 attached to the threaded end portion of hose coupling 12. Valve stem 31 is slidably supported within the chamber 24 by a centrally disposed bearing 30 which may be integral with the chamber wall. Stem 31 has its free end disposed for 35 contact by the inner end of the lever 21.

20 Lever 21 is mounted in sealed engagement with the walls of chamber 24 in the following manner to provide free pivotal movement of said lever about its fulcrum. An auxiliary chamber 35 is 40 provided below chamber 24 to communicate therewith through aperture 36. The upper end of lever 21 projects through aperture 36. Chamber 35 is defined by the walls of an annular closure 37 which has its upper portion in screw-thread relation with a depending annularly flanged portion of the casing wall. A pair of brackets 38 have their upper termini secured to the casing wall within said annularly flanged portion of the wall and beside the aperture 36. 45 Brackets 38 depend into chamber 35, lever 21 being fulcrumed between the brackets by means of a pintle bolt 34.

50 Lever 21, as best shown in Fig. 3, comprises an upper portion 40 which may have relatively flat sides and tapered ends, as shown, a lower

cylindrical portion which is threaded at 41, and an intermediate flange 42 which is rounded convexly in a downwardly direction adjacent the threaded section 41. Annulus 37 has its lower walls provided with a centrally disposed downwardly tapering aperture through which lever 21 projects. A cup-shaped sleeve-like sealing element 45, of flexible material encloses the fulcrumed portion of the lever and has its upper margins clamped in sealing engagement between the casing wall and the upper margins of annulus 37. The lowermost portion of sealing element 45 is apertured to receive the threaded section 41 of lever 21. Lower portions of element 45 marginally of said aperture are clamped in sealing relation with the convex surface of flange 42 by means of a complementary dished washer 46 which is likewise apertured to receive the threaded portion 41, and is held by a nut 47 of complementary form threaded to the lever 21. Washer 46 is adapted to substantially fill the bottom wall aperture of annulus 37 to prevent dirt from accumulating within chamber 35. Packing 45 is (for gasoline nozzle usage) preferably made of a gasoline-proof rubber substitute of which there are several types now on the market. Other materials may be used provided they possess the ability to withstand distortion and are not subject to attack by the liquid which is dispensed through the device.

An alternate embodiment of the fluid sealing means above described is disclosed in Fig. 3. In this embodiment the rubber, or rubber-like packing 45 is replaced by a bellows type metallic element 450, likewise cup-shaped, and preferably of copper. Element 450 is installed in a manner identical with that above described. The bellows construction of element 450 permits the use of a metal or other material which is not possessed of a resiliency factor great enough to enable its use in the form shown at 45.

In either case, the cup-shaped form of the packing, and the specific mounting of the lever 21 make possible ready access to the fulcrum pin 34 in the assembly or repair of the device. Removal of annulus 37 and downward folding or removal of the packing cup leaves the pintle 34 fully exposed. But for this structure the mounting of a lever in the wall of a nozzle would involve serious assembly and packing problems.

Operation of the device is as follows:

During use, an operator's fingers encircle handle 15, Fig. 2, in a position to actuate the handle toward casing 10 as shown in Fig. 1. During this operation roller 17 rides up the complementary arcuate portion of lever 16 to oscillate that lever in a counter-clockwise direction as viewed in Fig. 2. An opposite side portion 19 of lever 16 contacts the lower portion of lever 21 to oscillate said lever about pintle 34. Upper portion 40 of lever 21 displaces stem 31 axially to move valve plunger 26 against spring 27 thereby opening the valve to allow fluid passage through the device. Upon release of handle 15, spring 27 again seats valve 26 against partition 22 and stem 31 oscillates lever 21 back to its initial position.

It will be observed that the operating handle 15 is not only unattached to the valve actuating lever 21, but its operation does not bring it into contact with that lever, its motion being modified and transmitted by the intermediate cam lever 16 in such a manner that the movement of lever 21 is relatively slow and graduated to avoid the possibility of injury or

displacement of the valve and its actuating spring by careless operation of the lever 15.

We claim:

1. In a hose nozzle for gasoline and similar fluids, the combination with a hollow casing laterally apertured and provided with inlet and outlet passages and an internally disposed valve seating with the fluid pressure and adapted for controlling fluid communication between said passages, of a lever provided with fulcrum means at a point outside the casing on the delivery side of the valve and having a portion projecting through said aperture for actuation of said valve, a cup-shaped flexible jacket composed of material impervious to gasoline and having an apertured bottom wall clamped to the operating end of the lever, said jacket enclosing the fulcrum means, with its inner margin expanded and fitted to the wall of the casing about the casing aperture, and a cup-shaped housing also having an aperture in its bottom through which the operating end of the lever extends and having its inner margin in clamping relation to the expanded margin of the jacket, one of the jacket clamping members on the lever being adapted to serve as a slide closing the housing aperture in all positions of lever adjustment.

2. A valved nozzle for gasoline and similar volatile fluids, having in combination with the nozzle an internal valve seating in the direction of fluid delivery and provided with an actuating spring normally urging the valve toward its seat, said nozzle having a lateral aperture in its wall at the outlet side of the valve flanked by fulcrum supporting outwardly projecting arms, a lever fulcrumed to said arms, with its working end extending through said aperture in a position to open the valve against the combined pressure of the fluid of said actuating spring, a sleeve-like cup-shaped flexible seal impervious to gasoline and arranged with one end clamped to the nozzle about its lever receiving aperture, and with the other end clamped to the lever on the opposite side of its fulcrum, a manually operable lever operating means, and an interposed oscillatory cam for transmitting graduated motion from the operating means to said lever.

3. A manually operable valve mechanism for gasoline and similar fluids, comprising the combination with a casing having inlet and outlet cavities normally separated by a valve in the inlet cavity seating in the direction of the outlet, the wall of the outlet cavity having an opening for a valve actuating lever, an exteriorly fulcrumed valve operating lever having a working arm extending through said aperture in operative relation to the valve, flexible sealing means for preventing leakage through said aperture, a separate manually operable lever, a guard carried by the casing and to which said manually operable lever is fulcrumed, and a movable member also carried by said guard in a position to be actuated by the manually operable lever during a portion of its stroke and adapted to transmit relatively slow motion to the valve actuating lever, whereby to prevent hammering and jerky movements of the valve.

4. A nozzle for controlling deliveries of gasoline and similar fluids, comprising the combination with a hollow casing provided with inlet and outlet passages separated by a ported valve seat, a spring actuated valve in the inlet passage movable to and from said seat, a lever having an actuating arm in the outlet passage in operative relation to the valve, an independently pivoted

manually operable lever, and cam means unattached to either lever and interposed in a position to control and graduate the movement of the valve lever.

5. In a nozzle for controlling deliveries of gasoline and similar materials, the sub-combination of a valve actuating lever having an intermediate fulcrum and provided with a working arm extending into the outlet portion of said nozzle, a sleeve-like flexible cup enclosing the fulcrumed portion of the lever, a relatively rigid housing clamping one end of the sealing member to the nozzle wall about the working arm of the lever, a flange on the other arm of the lever, and adjustable clamping means on the lever adapted to hold the outer end of the seal in pressure engagement with the flange; said adjustable clamping means comprising a movable part of the housing wall adapted to keep the sealing member enclosed in various positions of lever adjustment.

6. In a hose nozzle for gasoline and similar fluids, the combination of a tubular casing provided with a spring actuated check valve and laterally apertured on the outlet side of said valve to receive a valve actuating lever having

10 an exterior fulcrum, a cup-shaped housing enclosing the fulcrumed portion of the lever and having threaded engagement with the casing, the bottom of the cup-shaped housing having an aperture through which the operating arm of the lever extends, a flange on said operating arm substantially in registry with the aperture of the housing and provided with a convex outer surface, a bowl-shaped slide having a concave surface corresponding to the convex surface of said flange and adapted for reciprocation in aperture closing relation to said housing when the lever is actuated, a cup-shaped rubber seal marginally clamped between the housing and the casing and having an apertured bottom portion engaged between the convex surface of said flange and the concave surface of the slide, and a clamping nut threaded to the operating end of the lever to hold the slide and seal in clamping relation to said convex flange surface, whereby the bottom of the sealing cup and said slide may oscillate within the housing and below the lever fulcrum during operation of the lever.
